Attorney

UNITED STATES PATENT OFFICE.

LOUIS A. MACKLAMBURG, OF OKLAHOMA, OKLAHOMA.

WEATHER STRIP.

Application filed May 9, 1923. Serial No. 637,840.

To all whom it may concern:

Be it known that I, LOUIS A. MACKLAMBURG, a citizen of the United States, residing at Oklahoma city, in the county of Oklahoma and State of Oklahoma, have invented certain new and useful Improvements in Weather Strips; and I do hereby declare the following to be a full, clear, and exact description of the invention, such as will enable others skilled in the art to which it appertains to make and use the same.

This invention relates to improvements in weather-strips and more particularly to metallic weather-strips.

15 The object of the present invention is to provide an improved weather-strip adapted to operate with the maximum efficiency both where a door or window and jamb fits snugly, and where a door or window and jamb fits loosely.

A further object of the present invention is to provide an improved structure for weather-strips by reason of which the passage of dust is effectively prevented.

25 Further objects will more particularly appear in the course of the following detailed description.

One sheet of drawings accompanies this specification as part thereof, in which like reference characters indicate similar parts throughout.

Figure 1 is a fragmentary perspective view of the improved weather-strip;

Fig. 2 is an end view of the strip applied to a door jamb shown in cross section the door (also in section) fitting loosely;

Fig. 3 is an end elevation of the strip applied to a door jamb shown in cross section where the door fits more snugly;

40 Fig. 4 is a fragmentary side elevation taken from the left of Fig. 2;

Fig. 5 is a fragmentary side elevation taken from the left of Fig. 3.

In accordance with the present invention a strip of suitable resilient metal is bent longitudinally on spaced parallel lines to form generally three plane surfaces 1, 4, and 6, the surfaces 1 and 6 being normally in substantially parallel but spaced planes while the intermediate plane surface 4 is at an acute angle thereto.

In practice beads 3 and 7 are provided, the former intermediate the plane surfaces 4 and 6, the latter on the opposite edge of plane 6, preferably terminating in an upturned lip 8. The plane part 1 is provided

with a plurality of spaced holes 9 adapted to receive the affixing nails or screws.

The above specified parts of the improved weather-strip are preferably so proportioned that when applied intermediate the door D and its jamb J, the beads 5 and 7 will both engage the edge of the door in its closed position, assuming that the door fits loosely, in which case the double spaced contact 65 serves to materially steady the door. In the event that the door fits more snugly the strip will be depressed, as illustrated in Fig. 3, so that the edge of the door will be engaged only by the bead 5 and the lip 8 will contact 70 the jamb. This operation is material, as in the flexing of metallic weather-strips there is a tendency to lift the parts of the strip intermediate the fastening members, as is illustrated in Fig. 5 as at 11, said lifting 75 of the strip permits the passage of dust. By reason of the improved structure above described, simultaneously with the lifting of the strip as referred to the lip 8 will contact with the jamb, thus sealing the passage and 80 preventing any air or dust which might enter at the points 11 from passing the door. At the same time with the more snugly fitting door the necessity for the double contact on its edge is eliminated, and with this 85 structure but a single point of contact is maintained.

The exact angle between the plane surfaces 1 and 4 at line 2 may, of course, be varied, and the bead 5 may be merged into 90 plane surface 4 as at 3, so that the surface 4 will furnish a smooth sliding surface for the door.

While the strip has been particularly described with reference to its application to doors, its structure has an equal utility in connection with windows or the like.

Having described my invention, what I claim as new and desire to secure by Letters Patent of the United States is,

An improved weather-strip of resilient sheet metal comprising a strip bent longitudinally to form two spaced plane faces substantially parallel and a third plane face intermediate and connecting the same, one 105 of said parallel faces constituting the attachment face and the other formed with a plurality of outwardly directed beads and having its free edge turned outwardly.

110 In testimony whereof I affix my signature.

LOUIS A. MACKLAMBURG.
